UNITED STATES PATENT OFFICE.

JOHN UTSMAN, OF FULLERTON, LOUISIANA.

LOADING-HOOK.

1,160,016.

Specification of Letters Patent.

Patented Nov. 9, 1915.

Application filed June 14, 1915. Serial No. 84,002.

To all whom it may concern:

Be it known that I, JOHN UTSMAN, a citizen of the United States, and a resident of Fullerton, in the parish of Vernon and 5 State of Louisiana, have invented a new and useful Improvement in Loading-Hooks, of which the following is a specification.

This invention relates to an improvement in loading hooks adapted more particularly 10 for use in loading logs and the like, and one of the principal objects of the invention is to provide a hook of improved construction, and having an adjustable cup and pin which may be removed when necessary, for 15 sharpening or substitution of new parts.

Another object of the invention is to provide an improved hook of the class described which will be extremely simple, durable, 20 efficient in operation and inexpensive to manufacture.

With these and other objects in view, which will become apparent as the description proceeds, the invention resides in the construction, combination and arrangement 25 of parts hereinafter more fully described and claimed, and illustrated in the accompanying drawing in which like characters of reference indicate like parts throughout the several figures, of which,

30 Figure 1 represents a view in elevation of a hook constructed according to my invention, Fig. 2 represents a vertical sectional view taken transversely therethrough, on the plane indicated by the line 2—2 of 35 Fig. 1, Fig. 3 represents a view in section taken horizontally on the plane indicated by the line 3—3 of Fig. 1, looking in the direction indicated by the arrows.

In carrying out my invention I provide a 40 hook, whose body portion is substantially right angular in shape and consists of a shank 5, having an eye 6 provided at its upper end for the reception of a hoisting cable or the like, and provided at its lower end 45 with a right angularly extending foot or toe 7. Toward the inner end of the foot, the same is provided with an opening or eye for the reception of a smaller rope or cable, not shown. The eye is indicated at 8, and the

50 material of the hook may be cut away adjacent the ends of the opening, if desired. The outer end of the foot is provided with a cylindrical enlargement 9 which extends substantially in parallel relation with shank 5, and which at its upper edge 10 extends or lies in a plane above the upper edge of foot

7. The cylindrical enlargement 9 is provided with a central tapered bore of downwardly decreasing diameter for the reception of a tapered pin 11. The latter is pointed at its upper end as at 12, and at its lower end is adapted to be mashed, or turned over, or flattened against the lower end of the enlargement 9, for riveting the pin in place, as indicated at 13. The cup consists of a 60 tapered body portion 14 having a central bore 15 for the reception of the cylindrical enlargement 9, over which said cup is adapted to fit. The upper end of the cup is hollowed out or concaved as at 16, and the 65 edges of the cavity are sharpened as at 17. Connecting bore 15 with the cavity 16 is a smaller tapered bore 18, through which pin 11 extends. The bore 15 thus terminates at its upper end in a shoulder 19 which rests 70 upon the upper end of the enlargement 9. The lower portion of the body 14 is provided, as clearly indicated in Fig. 3, with a radially extending recess or slot 20 for the reception of the outer end of foot 7, said slot 75 or recess being of a width substantially equal to the thickness of the foot. This recess extends from the bore 15 to the periphery of the cup, and from the lower end of said cup to a point adjacent the shoulder 19. The cup 80 thus engages upon the foot 7 in such manner as to be retained against rotary movement relatively to the foot. When it is desired to resharpen or replace the cup 14, the same may be lifted off the hook subsequently to 85 the removal of the pin 11, said cup being maintained against removal from the hook by reason of the tapered pin engaging in the smaller tapered bore 18 of the cup. When it is desired to remove the pin for 90 renewal or sharpening, the lower riveted end thereof may be sawed or filed off, and the pin readily removed.

Although I have described the preferred embodiment of my invention, I may desire 100 to make such changes in the construction, combination and arrangement of parts thereof, as do not depart from the spirit of the invention and the scope of the appended claims.

105 I claim:

1. The herein described hook, comprising a body portion consisting of a shank having an eye formed at one end thereof and having a right angularly disposed foot formed at 110 the other end thereof, said foot being provided adjacent its inner end with an eye, and

being provided at its outer end with a cylindrical enlargement, said enlargement having a tapered bore provided therein, a tapered pin adapted to be disposed within the bore, and being provided with a point at its upper end and adapted at its lower end to be mashed upon the enlargement for maintaining the pin in place, and a cup, said cup being provided with a central bore for the reception of the cylindrical enlargement, said cup being provided at its upper end with a concaved portion provided with sharpened edges, said cup having a tapered bore connecting the first said bore with the cavity and through which the tapered pin extends, said cup being further provided with a recess extending from first said bore to the periphery of the cup and adapted to receive the outer portion of said foot, substantially as described.

2. The herein described hook, consisting of a right angularly formed body portion having an enlargement at one end, a cup provided with a bore for the reception of the enlargement and with a recess for the reception of the adjacent portion of the body, said cup being concaved at its upper portion and having the edges of the cavity sharpened,

and a pin arranged axially with respect to the cup and having a pointed end extending beyond said cup, said pin being detachably engaged with the enlarged portion of the hook.

3. A device of the class described, comprising a body portion having an enlargement at one end, said enlargement being provided with a tapered bore, a tapered pin detachably disposed within said tapered bore, and being sharpened at one end, a cup having a bore receiving the enlarged portion, said cup being adapted to engage said body whereby to prevent rotation of said cup, said cup being provided with an annular sharpened edge surrounding the pin.

4. The herein described hook consisting of a body portion having an enlargement at one end, a tapered pin arranged within a bore provided in the enlargement and being mashed over at its smaller end against said enlargement, and a cup detachably arranged upon the enlargement and held against rotation thereon and encompassing said enlargement, said cup providing an annular sharpened portion surrounding the pin.

JOHN UTSMAN.
